UNITED STATES PATENT OFFICE.

JAMES P. GIBBONS, OF SPRINGFIELD, ILLINOIS.

CAR-CAGER.

1,083,207.

Specification of Letters Patent. Patented Dec. 30, 1913.

Application filed February 26, 1913. Serial No. 750,840.

To all whom it may concern:

Be it known that I, JAMES P. GIBBONS, a citizen of the United States, residing at Springfield, in the county of Sangamon and 5 State of Illinois, have invented new and useful Improvements in Car-Cagers, of which the following is a specification.

My invention relates to improvements in car-cagers for mines, of the type adapted 10 to automatically place loaded mine cars on the cage of a mine, and to remove the empty cars from the cage without the necessity of manual labor in performing these operations.

15 An object of my device is to provide a means for slowing down a number of loaded cars when run into the mine bottom so that they may not run into the sump, this operation to be performed without the manual assistance of a spragger.

Another object of my invention is to provide means for releasing a loaded car from the above mentioned braking device and to allow it to run down an inclined track into 25 position to be automatically loaded on a cage.

A further object of my invention is to provide a stopping and releasing device which will hold a loaded car in position to 30 be loaded, and which will automatically release said car and allow it to run on a cage when acted upon by the descending cage.

To accomplish all of these objects, and to secure further advantages in construction 35 and operation, my improvements involve certain new and useful peculiarities of construction, arrangement, and combination of parts, as will be herein fully described and pointed out in the appended claims.

40 The preferred embodiment of my invention is illustrated in the accompanying drawings to which I now refer.

In the drawings: Figure 1 is a fragmentary plan view of the device of my invention, in position at the bottom of a mine shaft. Fig. 2 is a fragmentary view of my invention, partly in section and partly in elevation. Fig. 3 is a detail sectional view of a portion of the braking device taken on 50 line 2-2 of Fig. 2. Fig. 4 is a front elevation of the stopping and releasing member, showing the movement of that member in the stopping and releasing position.

Referring to the drawings, 1 designates 55 inclined tracks upon which mine cars 2 are adapted to travel, track 1 terminating at

the sump of a mine shaft designated as 3. The cages, not shown, are adapted to travel upward and downward in shaft 3, the floor of the cages having tracks which are a continuation of tracks 1 of the mine. The tracks on the cages, when the cages are in position for loading cars, are adapted to be on a plane with tracks 1 of the shaft bottom. There being two tracks on the mine 60 bottom and two cages adapted to ascend and descend in shaft 3, it is not thought necessary to refer to but a single track as the arrangement of the device is the same for both sides of the shaft.

70 Numeral 4 designates an actuating member adapted to slide upward and downward in guide members 5 on the side of the sump of the mine shaft, actuating member 4 having rigidly attached to it a cable member 6 which passes over a pulley or sheave wheel 7 located in the center of the tracks leading to the shaft. Pulley 7 is counter-sunk into the track, allowing the cable member 6 to extend slightly above the level of the ties. 75 Cable member 6 extends backward from the mine shaft parallel with the rails of track 1 and is attached to an eye-bolt 8 which pivots bell cranks 9 together. Bell cranks 9 are L-shaped and are pivoted to foundation 80 members 11 located below the level of track ties, at points designated as 12, bell cranks 9 being adapted to move about pivot points 12 under the rail members of track 1. The outer arms of the bell crank members are 85 provided with stopping and releasing heads 10 which are normally in upright positions above the rail members. Stopping and releasing members 10 are provided with curved inner faces 13 which are adapted to conform 90 to a portion of the circumference of the wheels of mine cars 2.

A spring member designated as 14 is provided with a hook adapted to catch in eye-bolt member 8, the other end of spring 14 100 being caught in stationary eye-bolt member 15 suitably anchored in the center of track 1. Spring 14 is adapted to normally draw eye-bolt member 8, the inner ends of bell cranks 9, and cable member 6 backward 105 away from mine shaft 3.

The portion of the device adapted to brake the mine cars as they come on to the bottom of the mine, consists of parallel brake beams 16 carried parallel to track 1 by a 110 series of link members 17 which are pivoted to the brake beams and to foundation beams

18. Foundation beams 18 are rigidly anchored to the upper side of the ties of track 1, and are carried on the outer side of the rail members. Brake beams 16 are adapted 5 to be normally held at sufficient distance from the rails of track 1 to allow the wheels of mine cars to pass thereunder. The inner faces 16' of brake beams 16 are on a plane with the inner faces of the rail members of 10 track 1. At both ends of the brake device, crank shaft members 19 are provided and extend across the track between the ties and under the rails, having arms 19' extending upward and pivoted at their upper ends to 15 brake members 16. Crank members 19 are also pivoted to foundation beams 18 on the under side of said beams at points designated as 20. One of the crank arms 19 is extended downward on one side of the braking device, forming arm 21, to which is pivoted at point 22 a brake rod 23. Brake rod 23 is pivoted at its other end to the lower end of an actuating lever 24. Lever 24 is pivoted at any point above pivoting point 25, which point may be designated as 26. Lever 24 is provided with a locking means 27 adapted to engage in ratchet 28 for the purpose of locking said lever in any desired 30 positions.

30. In operation, it will be readily seen that as the bottom of a mine cage descends into sump 3 below the level of track 1, that the lower side of the bottom of the mine cage will engage with actuating member 4, forcing it downward along guide members 5. Cable member 6 will be drawn down at its 35 lower end over pulley 17, drawing with it the inner ends of bell cranks 9, which will actuate stopping and releasing members 10 outward about pivoting points 12, allowing a mine car which has been held from movement toward the shaft by heads 10, to move along inclined track 1 on to the cage then located on a level with track 1, forcing the 40 empty car on the cage off the cage on to a track on the opposite side of shaft 3. When the cage ascends, spring 14 will draw the inner ends of bell cranks 9 backward to their 45 normal position, throwing stopping and releasing members 10 back into position over the rails ready to catch the next car which 50 may run downward along the track.

The braking device is adapted to be located at some distance back from the shaft 55 openings and is adapted to be operated by an attendant on the mine bottom. In actual use, brake beams 16 are preferably of sufficient length to cover the wheels of three or four mine cars. It will be readily seen that 60 when a trip comes into the bottom of a mine, that the attendant, by actuating lever 24 backward and forward may cause friction to be set up between brake beams 16 and the wheels of mine cars, causing the same to 65 slow down and come to rest. When the cars

have become stationary the lever can be locked in ratchet 28, holding the cars in a braked position so that they may not travel down the inclined track. The attendant may then release the cars from the braking device for a sufficient length of time to allow one of the cars of the trip to travel out from under brake beams 16, locking the brake after the release of one car. The car can then be thrown on to either track desired, 70 by a switch, not shown, which is usually provided for this purpose in a mine. The car will then be caught by the stopping and releasing device and held in position there until the device is actuated by a descending 75 mine cage.

From the foregoing description it will be readily seen that the device of my invention provides an effective means of slowing down and braking trips of mine cars; that a car may be released from said braking device and allowed to run onward to a stopping and releasing device where it will be held until released; and that an automatic means is provided whereby a car may be released 80 from a stopping and releasing device and allowed to run on a cage, pushing off an empty car in place thereof, when actuated by said descending mine cage.

Changes within the spirit and scope of the 85 appended claims may be made as it is obvious that the details of construction and arrangement of parts may be varied in many ways.

Having thus described my invention, what 90 I claim is:—

1. The combination in a device of the character described, of an actuating member provided with slide members adapted to engage with guide members carried in the 105 wall of a mine sump, said actuating member being adapted to extend at right angles to said wall and having a cable member connected thereto, a cable member, a sheave wheel, bell crank members, stopping and releasing members carried by bell crank members, a coil spring member, a braking device, and means for operating said braking device, substantially as described.

2. The combination in a device of the 110 character described, of an actuating member, a cable member connected at one end to an actuating member and at the other end to an eye-bolt member pivotally connected to bell crank members, said cable being carried over a sheave wheel in a mine track, a 115 sheave wheel, bell crank members, stopping and releasing members, a coil spring member, a braking device, and means for operating said braking device, substantially 120 as described.

3. The combination in a device of the 125 character described, of an actuating member, a cable member, a sheave wheel countersunk in a mine track and adapted to carry a 130

cable member, bell crank members, stopping and releasing members, a coil spring member, a braking device, and means for operating said braking device, substantially as described.

4. The combination in a device of the character described, of an actuating member, a cable, a sheave wheel, L-shaped bell crank members mutually pivoted together 10 by an eye-bolt member and each pivoted to a stationary foundation at the angle, said bell crank members having a raised stopping and releasing head on their outer arms, a coil spring member, a braking device, and 15 means for operating said braking device, substantially as described.

5. The combination in a device of the character described, of an actuating member, a cable member, a sheave wheel, bell 20 crank members, stopping and releasing heads carried on the outer arms of bell crank members, said stopping and releasing heads being raised to an upright position above rail members of a track, the inner 25 faces of said heads being curved to conform to a portion of the circumference of the wheels of mine cars, a coil spring, a braking device, and means for operating said braking device, substantially as described.

30 6. The combination in a device of the character described, of an actuating member, a cable, a sheave wheel, bell crank members, stopping and releasing members, a coil spring member having its outer end anchored in the center of a track and its inner 35 end attached to the pivoting pin of said bell crank members, a braking device, and means for operating said braking device, substantially as described.

7. The combination in a device of the character described, of an actuating member, a cable, a sheave wheel, bell crank members, stopping and releasing members, a coil spring, a braking device having two parallel 40 brake beams carried parallel to the rails of a track, said parallel beams being connected by a series of pivoted link members to foundation beams carried on the tie members of said track, said brake beams being normally positioned at sufficient distance above 45 said rails to permit the passing of car wheels thereunder, said brake beams being connected to each other by crank shafts passing beneath the rails of said track and having crank arms at right angles to said 50 crank shafts, said crank arms being pivoted to said brake beams adjacent both ends thereof, one of said crank arms being extended below said crank shaft and adapted to connect with means for operating said 55 braking device, and means for operating said braking device, substantially as described.

8. The combination in a device of the character described, of an actuating member, a cable, a sheave wheel, bell crank members, stopping and releasing members, a coil spring, a braking device, a brake rod pivoted to one end of a braking device and at the other end to a brake lever, said brake 65 lever being pivoted at a point above said 70 brake rod and having a handle and locking means to secure said lever in different positions, substantially as described.
